Patented Apr. 12, 1927.

1,624,091

UNITED STATES PATENT OFFICE.

CHARLES C. COLBERT AND GEORGE E. PRESTON, OF ELKHART, INDIANA, ASSIGNEES
TO AMERICAN COATING MILLS, OF ELKHART, INDIANA, A CORPORATION OF IN-
DIANA.

COATED PAPER BOARD.

No Drawing. Original application filed July 2, 1923, Serial No. 648,883, now Patent No. 1,514,439, and in Canada October 14, 1924. Divided and this application filed October 23, 1924. Serial No. 745,527.

Coated paper board of highly desirable quality, having advantageous stiffness and snappy character, has been produced by the present inventors by a process disclosed in 5 their Patent No. 1,514,439, dated November 4, 1924, to which reference is hereby made as a part of this specification.

The process referred to involves formation of the board from wet stock in a continuous web while successively treating the same to produce the finished coated product, without reeling the board or rolling it upon itself during manufacture and without subjecting the board to such influences as to impair 10 the natural rigidity inherent in the material of which the board is composed.

In conducting such process, the continuous web of board running from its source of production is stored in relatively stagnant accumulations alternating with lineally running portions of the board; and the coating operation is conducted while drawing the board with appropriate tensioning from a preceding accumulation; while the finishing 15 operation is conducted while drawing the dry coated board from a succeeding accumulation, likewise under appropriate tensioning conditions.

These accumulations are flexible in the sense that the quantity of board stored therein is variable to permit continuity of production of the board from wet stock and continuity of delivery of the finished coated product while permitting temporary interruptions 20 in the coating operation as may be necessary for changing materials, cleaning brushes or other necessities.

An illustrative practice of the method aforesaid, as described in said patent, is set forth in the following description.

In said patent, there is shown for example a paper board-making machine of the type comprising a series of cylinder molds which successively apply layers of pulp to an endless felt to form the wet laminated board web. Ordinarily the board is composed of different classes of stock, for instance cheap newspaper stock for the intermediate layers and white manila stock for the surfaces of 45 the board or at least the surface which is to be calendered and coated.

The wet board web forming continuously on the felt is carried between appropriate presses or squeeze rolls, which squeeze out

the surplus water from the web; and the web 55 is then passed through appropriate presses and thence through drying equipment, for instance a series of steam heated cylinders or drums in contact with which the web is carried; and the web is then run through one 60 or more sets of calendering rolls from which it is continuously delivered in dry and calendered condition. The calendered surface of the board for application of the liquid coating is usually supplied by the liner of 65 white or superior stock from one cylinder mold, this being the top surface of the board.

The calendered board is delivered into a flexible accumulation which in the patent referred to is provided by apparatus for hanging up the board in festoons or folds. The capacity of this apparatus is such as to store a large quantity of the hanging festoons of board, whereby the freshly produced raw board, before undergoing the coating operation, is subjected to a seasoning process by prolonged exposure to the atmosphere while in hung-up condition. Provision is made for varying the number of hanging festoons in the apparatus so as to permit continued 70 accumulation of the continuously supplied board in hung-up condition in the delivery 75 end of the apparatus, during temporary interruptions in the operation of the coating machine; and the excess accumulation thus 80 stored may be drawn off after resuming the coating operation by temporarily speeding the coating appliance, thus restoring normal 85 conditions.

From the accumulation in the hang-up apparatus, the board is drawn through a coating machine in such manner as to take up the slack gradually and to tension the board for coating without subjecting it to sharp flexing or sudden stresses in its transit from 90 the slack condition to tensioned state. This may be accomplished by drawing the board in contact with suitable rollers arranged to deflect the course of travel of the board, one or more of which rollers may be frictionally 95 retarded to impose a resistance to the passage of the board thereover, or the board may be drawn over a frictional surface in advance of drawing it over guide rollers to the coating machine. The board is also 100 guided to the coating machine in such manner as to expose on the cylinder of said machine the top calendered surface of the 105

board, which in passing through the machine receives the liquid coating, and to deliver the board coated side uppermost from said machine. The coating applied to the 5 board is usually a liquid coating such for instance as a solution of clay and casein with or without coloring pigments, which may be applied by a rotating brush supplied with the coating liquid from a fountain roll, and the liquid is brushed thoroughly into the board by reciprocating brushes as the board passes through the coating machine.

The coated board delivered from the coating machine is accumulated in hanging festoons or folds and subjected to drying action, which as described in said patent is conducted in a drying room through which the hanging festoons of board are slowly 10 conveyed; and provision is made through the heating arrangements of the drying room and by occasional shifting of the points of suspension of the festoons of board for subjecting the web to substantially uniform 15 drying treatment. Beyond or at the delivery end of the drying room a number of the hanging folds of dry coated board are collected in a flexible supply providing a reserve from which the board may be withdrawn 20 for the ensuing finishing operation during temporary interruptions of the coating operation, which interruptions are accompanied by stoppage of the drying room conveying system; and the reserve supply 25 referred to may be replenished upon resumption of the coating operation by the temporary speeding up of the coating machine for withdrawal of the excess accumulated in the preceding accumulation from 30 which the board is drawn for coating.

From the accumulated supply at or beyond the delivery end of the drying room, the dry coated board is drawn through a supercalendering machine for the finishing operation. Preceding the supercalendering machine are appropriate means for smoothing and progressively tensioning the board until it is drawn with requisite tenseness for the supercalendering operation. For these 45 purposes the board may be drawn over a curved frictional surface or surfaces and around frictionally retarded rolls. Cooperating with these smoothing and tensioning agencies are means for aligning the board web and for overcoming any tendency to run at a bias or the like, which, in conjunction with the drawing of the board tense, minimizes tendencies to creasing or 50 wrinkling of the board as it is drawn into the rolls of the supercalendering machine.

The supercalendering machine irons out the board and imparts a sheen or gloss to its coated surface, and if desired the finishing 55 of the coated surface of the board may be effected in part by agencies supplement-

ing the finishing action of the supercalendering rolls.

From the supercalendering machine the board may be passed through a synchronously operating cutting machine which subdivides the board and delivers the product in cut flat sheets ready to be immediately packaged for shipment. In some instance, to comply with particular trade requirements, it may be desired to package the 70 board in rolls, in which case the finished product may be delivered to an appropriate reeling machine.

The method above described has important effects upon the quality of the product, particularly as to stiffness and snappy character. From the period of formation of the raw board from the wet stock until the delivery of the finished product, the board is maintained in an open distended condition, 80 there being no intermediate reelings and un-reelings of the board or lapping it upon itself; and the successive operations which the board undergoes are such as to stress every portion of the board uniformly and 85 to produce a substantially uniform setting of the fibrous structure having a general tendency to straightness, no portion of the board being flexed under tension at any different radius than other portions. Moreover there is no repeated or prolonged bending of the board back and forth upon itself between successive stages of manufacture 90 such as to weaken the natural rigidity of the fibrous structure of the board. During 100 the greater portion of the entire time between the calendering of the raw board and the delivery of the finished product, the continuous board web is stored in relatively 105 stagnant accumulations between successive machines, and the sheet is tensioned only in running it through successive machines. Furthermore the transition of the web from slack to tensioned condition is gradual or 110 without sudden severe stretching, and there is comparatively little flexing or bending of the sheet under tension, while such flexing as occurs is only of momentary duration on the portion of the running board in course 115 of treatment. Hence the board remains wholly unaffected by intermediate reeling and substantially unaffected by sharp bending or flexing back and forth under tension. This results in a substantially uniform condition 120 of all portions of the fibrous structure of the board in a state promoting stiffness and flatness, and the product has the maximum stiffness and snappy character consistent with the constituency and thickness of the board material.

Prior to the present invention, the ordinary commercial manufacture of coated board involved the production of the raw board in a board-making plant; reeling the output from the board-making machine and 125

then unreeling and passing it through a trimming machine and rereeling it into even edged rolls; transporting these rolls to a coating machine; mounting the rolls one at 5 a time in a reel associated with the coating machine; drawing the board through the coating machine and then through a drying room; reeling the coated board delivered from the drying room and unreeling and re- 10 reeling it to form an even edged roll; removing the roll of coated board to a calendering or finishing machine, and again mounting it in a reel, drawing it through the finishing machine and reeling, unreeling 15 and rereeling the finished board into an even edged roll, either for merchantable purposes or for removal to still another machine through which the board was drawn from the roll and cut into sheets.

20 Thus the board material, between the stages of production of the raw board and the delivery of the finished coated product, was repeatedly reeled, unreeled and rereeled, thereby subjecting the fabric to strain and 25 flexure under tension, with consequent tendency to diminish the stiffness and snappy characteristic of the board. Furthermore the storage of the board in rolled-up condition between successive stages of manufac- 30 ture caused it to set in rolled-up form, with consequent tendency to resume its curvature during ensuing stages of treatment and in the finished state, thereby diminishing the 35 capacity of the board to stand up stiff in the carton. As the board in the rolls set with its successive layers at different radii, there

was accordingly a different state or condition of the fibrous structure of the board all along the length thereof, tending to promote buckling or unevenness of the product 40 for use in a carton or the like; while the board otherwise was inevitably impaired as to rigidity.

Coated board manufactured in accordance with the present invention may be used in 45 lieu of thicker board produced by the ordinary commercial method above referred to. For instance, coated board of .0014 inch thickness, made by the present method, may be used and is satisfactory for manufacture 50 of cartons in place of board of .0016 inch thickness made by said ordinary method.

We claim:

Paper board composed of consolidated layers of paper material including an outer cal- 55 endered liner having a finished coated surface, the fabric structure of the board being of a substantially uniform set and retaining substantially the maximum rigidity inherent 60 in the material of which the board is composed, and the board possessing a pronounced stiffness and snappy characteristic, such fabric structure being characterized by its manufacture from the wet stock to the finished coated product without rolling 65 up or lapping the board upon itself or subjecting it to severe flexing under tension.

In testimony whereof, we have signed our names to this specification.

CHARLES C. COLBERT.
